(57) CLAIM

The ornamental design for a catnip toy, as shown and described.

DESCRIPTION

FIG. 1 is a perspective view of a catnip toy showing my new design;

FIG. 2 is a front view of FIG. 1;

FIG. 3 is a rear view of FIG. 1;

FIG. 4 is a right side view of FIG. 1;

FIG. 5 is a left side view of FIG. 1;

FIG. 6 is a top plan view of FIG. 1; and,

FIG. 7 is a bottom plan view of FIG. 1.

The broken lines on FIGS. 1-3 and 6 represent stitching, are for illustration only and form no part of the claimed design.
